COIN-CONTROLLED MECHANISM.

1,164,856.

Specification of Letters Patent. Patented Dec. 21, 1915.

Application filed June 21, 1915. Serial No. 35,310.

To all whom it may concern:

Be it known that I, PHILIP D. PARSONS, a citizen of the United States, and resident of Philadelphia, county of Philadelphia, and 5 State of Pennsylvania, have invented an Improvement in Coin-Controlled Mechanism, of which the following is a specification.

The object of my invention is to provide a coin controlled mechanism adapted to dispensing devices whereby upon the deposition of a single coin a plurality of the articles to be vended may be liberated or discharged. More particularly, my object is to provide a coin controlled delivery device for dispensing paper towels, whereby a plurality of towels may be released or delivered upon the deposition of a single coin.

Heretofore, coin controlled devices have been constructed for delivering an article 20 upon the deposition of one or a plurality of coins, but as far as I am aware, no coin controlled device has been provided for successively delivering a plurality of articles upon the deposition of a single coin, either 25 automatically or by the manipulation of a manually operated part.

More specifically, my object is to provide a manually operated mechanism for directly acting upon articles to be vended; 30 and in which said manually operated part is rendered inactive except when a suitable coin is deposited in the device and which manually operated mechanism may be manipulated for a predetermined definite number 35 of times to cause successive articles to be delivered before becoming again inoperative.

In carrying out my invention, I provide means for operatively delivering a suitable 40 article to be vended, combined with hand operated means capable of having its available movements repeated, and coin controlled mechanism intermediate of said means for operatively delivering the articles 45 and the hand operated means, whereby with a single coin the hand operated means may maintain a mechanically operative relation with said means for imparting thereto a predetermined definite number 50 of operations to cause a plurality of articles to be delivered in succession.

More specifically, my improved mechanism comprises a positively operated part, an intermittently operated part, and an intermediate coin controlled part so con-

structed and arranged that the deposition of a single coin will enable the positively operated part to actuate the intermittently operated part for a plurality of intermittent operations.

My invention also comprehends other features of construction which, together with those above specified, will accomplish the above recited and other objects, and the nature of which improvements will be more fully understood from the descriptions hereinafter contained.

Referring to the drawings:—Figure 1 is an end elevation with part in section of a coin controlled delivery mechanism applied to a dispensing cabinet, more particularly intended for dispensing paper towels; Fig. 2 is a front sectional elevation of a portion of the same taken on line $x-x$ of Fig. 1; Fig. 3 is a sectional elevation of the coin controlled mechanism taken on line $y-y$ of Fig. 4; Fig. 4 is a cross sectional view of the same taken on line $z-z$ of Fig. 3; Fig. 5 is a perspective view of one of the parts of the coin controlled mechanism removed; Fig. 6 is an elevation of the same; Fig. 7 is a disk and pawl element of the coin controlled mechanism; and Fig. 8 is a sectional elevation through the manually controlled part of the mechanism.

2 is a cabinet adapted to support towels or other articles and having a suitable discharge orifice indicated in dotted lines at 3.

4 is a curved sheet metal blade adapted to push the articles to be delivered through the orifice 3, and may be rocked in one direction by a shaft 5 and the manually operated mechanism and returned into its normal or initial position by a spring 6. This mechanism for causing a discharge of the article may be of any other suitable construction, as my invention is adapted to any suitable cabinet or dispensing device which delivers an article by an intermittent movement of a movable part, and hence the particular pivoted blade structure 4 with the special opening 3 is given by way of example and not as a restriction to the utility of my invention. To the outside of the cabinet 2 and at one end thereof, I provide a casing 7 containing the coin actuated mechanism 8 and also acting as a coin receiving compartment. The bottom of this compartment may be closed by a hinged door 9 retained in position by a suitable

lock 10 of any desired character. The upper portion of this casing 7 may be provided with a coin receiving slot 12 which delivers the coin directly into the slot 39 of the coin operated devices. The operating lever 13 for actuating the coin operated mechanism or devices extends upwardly through a slot 14 in the casing 7 so as to be in position to be manually operated. In the normal 10 operation, the coin is deposited in the coin slot 12 and enters the coin receiving aperture 39 of the mechanism 8, and by its presence enables the manually operated arm or lever 13 to be connected with and operate 15 the shaft 5 to impart to it a predetermined given number of oscillations before the connection between said parts becomes released, and I will now describe in detail the mechanism for accomplishing these results.

20 The parts 15, 16 and 17 provide a cylindrical case, the part 17 provided with a central laterally extending bearing 18, and the part 15 being apertured to provide a circular bearing 19. Journaled within the bearing 25 19 and upon the journal 18 is the coin receiving part 20, illustrated more particularly in Figs. 3 to 6 inclusive. The shaft 5 extends through the casing 7 and is provided on its end with a hub 21 having a tooth 22, said 30 hub and tooth arranged within the apertured portion 23 of the coin receiving part 20 and adapted to contact in succession with the teeth 24 thereof. By reference to Fig. 7, it will be observed that the axis of the 35 shaft 5 is eccentric in respect to the bearing 19, and as the bearing 19 receives and centralizes the coin receiving part 20, it will be manifest that as the said part 20 is rotated while supported by said bearing 19, the inwardly directed teeth 24 of said part will 40 successively contact with the tooth 22 to rock the shaft 5, and owing to the eccentricity as to arrangement of said shaft, will release the tooth 22 and its shaft after a given rotation has been made, the spring 6 returning 45 the shaft to its normal position. It will be understood that if this coin operated part 20 were continually rotated, there would be a repetition of the oscillating movements 50 given to the shaft 5 and the discharging or delivery blade 4. The perimeter of the apertured part 23 is notched as at 25 so as to cause the outer portion to constitute substantially a ratchet wheel. These notches 55 are engaged by a gravity actuated detent 26 in the part 15 of the case so as to prevent a backward rotation of said part 20. Any other suitable manner of preventing back rotation may be employed in lieu of that 60 shown. The coin receiving part 20 is also provided at its other outer portion 28 with a cylindrical socket 27 which fits over the journal bearing 18 of the casing part 17, and is thereby held in proper position transversely in the case and also supported axially.

The outer portion 28 adjacent to this socket 27 is also provided with notches 29 similar to the notches 25, but in this case there are only two of these notches and these provide in effect two ratchet teeth. Between the 70 apertured part 23 and the socket portion 28, there is a transverse slotted passageway 30 through which the coin passes, and this passageway is formed by the spacing blocks 31 interposed between the parts 23 and 28. It 75 is also to be understood that the perimeters 32 of these blocks are preferably portions of the same circle, and the forward ends thereof 33 may act as ratchet teeth for engaging the pawl 34 pivoted at 35 to the stationary 80 part 15 of the casing, as will be clearly understood by reference to Fig. 3. This engagement of the pawl 34 prevents a forward rotation of the coin receiving part 20, except when the said pawl is lifted out of engagement by the coin. The width of the passageway 30 between the two spacing blocks 31 is slightly in excess of the diameter of a ten cent piece but not quite equal to the diameter of a cent, the latter being indicated 85 in dotted lines at 36 in Fig. 3. The blocks 31 are also slightly beveled at their ends to form a tapered socket for receiving and seating the coin, as will be understood.

In addition to the parts which have thus 90 been described, there is the manually operated part more fully indicated in Fig. 8 which is shown within the casing, the latter being in section. This manually operated part consists of an annular frame 37 which 100 is notched at the bottom as at 38, and is also provided with an upwardly extending lever or knob 13 by which it is rocked and a lug or tooth 40 projecting laterally from its upper portion. The manually operated part 105 37 is further provided with a spring actuated detent 41 which is radially movable under the action of a spring 42 and is adapted to engage the ratchet teeth formed by the notches 29 in the part 28, and by means of 110 which the coin receiving portion is caused to be intermittently rotated. A spring 43 is coiled about the stud or bearing 18 having one end attached thereto and the other end connected with the annular manually operated part 37 so as to normally move it into the initial position indicated and always to return the said part to this position whenever released.

The constructions shown in Figs. 6, 7 and 120 8 are intended to illustrate the dismantled parts illustrated in Figs. 3 and 4. The part 20 illustrated in Fig. 6 is dropped into the part 15 so as to be journaled in the bearing 19 and to extend over the parts 5, 21 and 22. The structure shown in Fig. 8 is then placed 125 over the part 20 when so assembled with the other parts, and in doing this the structure shown in Fig. 8 is inverted so that the part which is exposed to the eye is turned under 130

and over the part 20 when assembled, which will all be understood by reference to Fig. 4. The part 20 will be properly journaled in the bearing 19 and on the bearing portion 18 5 so that it is capable of proper operation during its intermittent rotation. It is to be understood that this invention is in no wise limited to the use of the oscillating discharging blade 4, as the shaft 5 may be employed 10 to operate any other suitable means of delivery for the article being vended, said part 4 being only shown by way of example.

It will now be understood that the part 37 15 may be manually oscillated and that the part 20 is operated thereby under certain coin controlled conditions, and moreover that the said part 20 in its intermittent rotary motion will impart a trip action to the shaft 5 and the delivery apparatus, and the 20 particular operation may now be stated.

The coin is inserted through the slot 12 and a slot 39 in the casing 16, and is received in the slot 30 of the part 20, as indicated in dotted lines in Fig. 3. When the 25 coin is thus moved into position, the rounded entering part strikes upon the end of the pawl 34 and lifts it out of engagement with the tooth end 33 of the part 20, thereby releasing this part so that it may be rotated.

30 The manually operated handle 13 is then pulled and the lateral lug 40 thereof contacts with the coin 36 and pushes it downward and through it moves the coin operated part 20 through an arc equal to 90°.

35 In doing this, the upper tooth 24 of the portion 23 strikes upon the tooth 22 of the hub 21 and thereby gives the shaft 5 a partial rotation. This rocks the blade 4 to discharge the article. As before pointed out,

40 the eccentric position of the axis of the shaft 5 in respect to the bearing 19 in which the coin controlled part 20 rotates causes the tooth 24 to release the tooth 22 just before a quarter of a revolution is made by the part 20. This allows the spring 6 to return 45 the blade 4 to its original position. The lever or manually operated part 13 is then allowed to swing back again under the action of the spring 43 to its initial position.

50 During the time that this is swinging backward, the detent 26 dropping into the notch 25 of the part 23 holds it against backward motion. When the lever 13 has returned to its original position, the detent 55 41 thereof snaps into the recess 29 of the portion 28 of the coin operated part 20, and when the lever 13 is again pulled forward, this detent 41 rotates the coin controlled part 20 and gives it a second rotary

60 movement of 90°, and by means of the next tooth 24 causes the tooth 22 to operate the blade 4 to make a second delivery of the toweling or other article. During this second movement, the same releasing of the

tooth 22 and the shaft 5 takes place so 65 that the blade returns to its original position and the coin 36 is permitted to drop through the slot 11 in casing part 16 into the compartment 7. When this operation has taken place there will have been two deliveries from the cabinet 2 and no further reciprocations of the lever 13 will have any effect upon the blade 4, unless there is another coin placed in position within the part 20. 75

From this construction and operation it will be seen that the first actuation of the delivering mechanism is performed by causing the manually operated part to transmit motion through the coin, and the subsequent 80 operation of the manually operated part transmits motion directly to the coin controlled mechanism, and as far as I am aware this feature of the invention is broadly new.

Should a ten-cent piece be inserted in 85 the slot 12, it will pass through the part 20 and be returned to the person through the return conduit 41, this being permitted by reason of the fact that the distance between the spacing blocks 31 is slightly greater 90 than the diameter of a ten cent piece and less than the diameter of a cent, as before pointed out, and hence there is no means of supporting a ten cent piece in operative position within the mechanism. The slot 12 95 is supposed to be of a size which would not take in a five cent piece, so that there would not be much opportunity to operate the box with anything but a cent. Of course, I do not in any manner limit myself 100 in this proportion, because this mechanism may be adapted to be operated by any coin to suit the value of the article, it merely being necessary to provide the proper shape of the coin receiving portions of the device. 105

It will also be manifest that while I have designed the coin controlled device for the purpose of delivering two articles in succession for the deposition of a single coin, it is evident that by properly proportioning 110 the parts and increasing the number of the teeth 24 and notches 25 and 29, three or more articles may be discharged with each deposition of a coin, and hence I do not restrict myself to any particular number 115 when I use the word "plurality" of articles.

It will now be apparent that I have devised a novel and useful construction which embodies the features of advantage enumerated as desirable, and while I have in the 120 present instance shown and described the preferred embodiment thereof which has been found in practice to give satisfactory and reliable results, it is to be understood that I do not restrict myself to the details 125 as the same are susceptible of modification in various particulars without departing from the spirit of the invention.

Having now described my invention, what I claim as new and desire to secure by Letters Patent, is:—

1. In a coin controlled mechanism, the combination of a movable part to be operated with an intermittent rotary reciprocating motion, mechanism independent of but for intermittently operating the said movable part in one direction and adapted to temporarily receive and hold a coin, a manually operated part adapted to engage the coin and through it impart preliminary movement to said mechanism in one direction, automatic means between the manually operated part and said mechanism for providing a connecting engagement for producing a secondary movement to said mechanism also in the same direction, whereby successive movements of the manually operated part cause the movable part to be reciprocated in a forward direction first through the application of the power to the coin and then by direct application of the power to the mechanism independently of the coin, and devices for normally returning the movable part to be operated to its initial normal position after each of said forward movements by the operation of the manually operated part.
2. In a coin controlled mechanism, the combination of a movable part to be operated, mechanism for intermittently operating the said movable part and adapted to temporarily receive and hold a coin, a manually operated part adapted to engage the coin and through it impart a movement to said mechanism, automatic means between the manually operated part and said mechanism for providing a connecting engagement for producing a secondary movement to the said mechanism, and means for providing intermittent engagement and release between the mechanism and the part to be operated, whereby successive movements of the manually operated part cause the movable part to be operated first through application of the power to the coin and again operated by direct application of the power to the mechanism independently of the coin.
3. In a coin controlled mechanism, the combination of a movable part to be operated, mechanism for intermittently operating the said movable part and adapted to temporarily receive and hold a coin, devices to lock the mechanism against rotation in a forward direction said devices being thrown out of operation by the deposition of a coin, a manually operated part adapted to engage the coin and through it impart a

movement to said mechanism, and automatic means between the manually operated part and said mechanism for providing a connecting engagement for producing a secondary movement to the said mechanism, whereby successive movements of the manually operated part cause the movable part to be operated first through application of the power to the coin and again operated by direct application of the power to the mechanism independently of the coin.

4. In a coin controlled mechanism, the combination of a movable part to be operated, mechanism for intermittently operating the said movable part and adapted to temporarily receive and hold a coin, devices to lock the mechanism against rotation in a forward direction said devices being thrown out of operation by the deposition of a coin, means to prevent a backward movement of the said mechanism, a manually operated part adapted to engage the coin and through it impart a movement to said mechanism, and automatic means between the manually operated part and said mechanism for providing a connecting engagement for producing a secondary movement to the said mechanism, whereby successive movements of the manually operated part cause the movable part to be operated first through application of the power to the coin and again operated by direct application of the power to the mechanism independently of the coin.

5. In a coin controlled mechanism, the combination of a movable part to be operated, mechanism for intermittently operating the said movable part and adapted to temporarily receive and hold a coin, means to prevent backward rotation of the mechanism, coin controlled means for normally preventing forward rotation of the mechanism but arranged to release the mechanism upon deposition of a coin, a manually operated part adapted to engage the coin and through it impart a movement to said mechanism, spring devices for returning the manually operated part to its initial position, and automatic means between the manually operated part and said mechanism for providing a connecting engagement for producing a secondary movement to the said mechanism independently of the coin.

In testimony of which invention, I hereunto set my hand.
